SYMMETRICAL DIQUATERNARY AMMONIUM COMPOUNDS

Jesse C. H. Hwa, Levittown, Pa., assignor to Rohm & Haas Company, Philadelphia, Pa., a corporation of Delaware

No Drawing. Application January 9, 1956
Serial No. 557,836

15 Claims. (Cl. 260—567.6)

The present invention relates to novel symmetrical diquaternary ammonium compounds and to a method for their preparation.

The symmetrical diquaternary ammonium compounds of the present invention may be represented by the formula

in which R₁ is preferably an alkyl group of no more than two carbon atoms, R₂ is preferably an alkenyl group of eight to twenty carbon atoms, E is preferably an alkylene group of two to four carbon atoms, and X is preferably a halogen having an atomic weight of about 35.5 to 127.

The symbol R₁ preferably represents a methyl or ethyl group, that is, an alkyl group of no more than two carbon atoms. The two R₁ groups on each of the nitrogen atoms may be taken collectively to represent a divalent saturated aliphatic chain of four to five atoms which jointly with the amino nitrogen atom forms a five- to six-sided monoheterocyclic amine group such as morpholino, thiamorpholino, pyrrolidinyl, and piperidino groups, and these groups having a lower alkyl substituent, such as a methyl or ethyl group.

The symbol R₂ is preferably an alkenyl group of eight to twenty carbon atoms. Actually, R₂ may be any aliphatic group, of the stated size, that has at least one bond of unsaturation. That is, there may be used alkenyl, alkydiethyl, alkyndyl groups, and the like, of eight to twenty carbon atoms. The R₂ group may be a straight or branched chain, preferably branched in any of the known spatial configurations and the bond or bonds of unsaturation may be at any possible locations. For instance, when R₂ is dodecenyl possible groups include n-dodecenyl, isododecenyl, 1,10-dimethyl-2-decenyl, 2,7-dimethyl-2-decenyl, 1-ethyl-2-methyl-5-nonenyl, 4-propyl-2-nonenyl, 5-butyl-2-octenyl, 1,2-diethyl-4-octenyl, 1-propyl-6-ethyl-3-heptenyl, and the like. A common commercial form of the dodecenyl group that yields a compound of this invention that is particularly effective for the present purposes is tetramethyloctenyl, in which there are two methyl groups on each of the number five and seven carbon atoms and the double bond is at the number two location. Typical of the R₂ representations include octenyl, nonenyl, decenyl, dodecenyl, tetradecenyl, pentadecenyl, hexadecenyl, octadecenyl, nonadecenyl, eicosenyl, octadienyl, decadienyl, dodecadienyl, octadecadienyl, octynyl, dodecynyl, and octadecynyl.

The symbol X is preferably a halogen having an atomic weight of about 35.5 to 127, i.e., chlorine, bromine, or iodine. Chlorine is the preferred representation of X. It will be apparent to one skilled in the art that other anions may be satisfactorily employed such as sulfate, methylsulfate, phosphate, acetate, citrate, tartrate, and the like, which may be supplied directly or by metathesis with the halide form of the present compounds or by

the use of an anion-exchange resin. Generally, an anion having a group weight of up to about 127 is desired.

E is a divalent aliphatic group of two to four carbon atoms, including an alkylene, alkenylene, or alkynylene group. E is preferably an alkylene group of two to four carbon atoms or an alkynylene group of four carbon atoms with the triple bond in the number two position. While E is, in most cases, entirely hydrocarbon, that is, made up of only carbon and hydrogen, there may be present a single hydroxyl substituent. E may be employed in any of its isomeric forms.

It is essential for the present purposes that the groups R₁, R₂, and X be the same on each of the nitrogen atoms, that is, the present compounds must be spatially symmetrical about the nitrogen atoms with respect to R₁, R₂, and X. The compounds of this invention, in order to be effective for the present purposes, are restricted as to the size and identity of the substituent groups, the symmetrical molecular configuration, and the presence 15 of aliphatic unsaturation, and preferable branched skeletal structure, in the R₂ groups.

The quaternary ammonium compounds are preferably prepared by bringing together at a reacting temperature, and thereby causing to react, a compound having the 20 formula

30 with a compound having the formula R₂X. The results are generally essentially quantitative. The reaction involves the union of the R₂X and

35 compounds on a two to one molecular basis in order to form the symmetrical diquaternization products of this invention. If desired, the R₂X reactant may be used in excess in order to assure completeness of reaction. Completeness of reaction may be indicated by the amount of ionizable anion formed, such as halide, and the disappearance of basicity. If an excess of R₂X is employed it may be removed at the completion of the reaction by 40 distillation or solvent extraction, as desired.

45 Reaction temperatures may be used in the range of about 25° C. to the reflux temperature of the reaction mixture, preferably from 50° to 125° C. or up to the reflux temperature, temperatures up to about 265° C. being practical. If desired, there may be used a catalyst, such as a polar iodide soluble in the reaction mixture. Sodium iodide is preferred in this respect.

50 Reaction times of about two to twenty hours or more are generally employed depending largely on the reaction temperature, solvent, and individual reactants used. The time of reaction is not critical but merely influences the yield. As will be apparent to one skilled in the art, the longer reaction times generally favor higher yields, up to a point, and, of course, some reactants unite more speedily than others.

55 It is advantageous to employ a volatile inert solvent such as hexane, heptane, benzene, toluene, ethyl ether, methanol, isopropanol, water, chloroform, acetone, 2-butanone, acetonitrile, acrylonitrile, nitromethane, formamide, dimethylformamide, succinonitrile, and the like. At the conclusion of the reaction the solvent may be removed by any conventional method, such as by distillation, preferably under reduced pressure or by filtration of the product. The symmetrical diquaternary ammonium product remains as the residue and is usually a clear-to-white, high-wetting, hygroscopic, crystalline solid or a tan-to-brown, heavy-oil semi-solid. These products 60

are substantially water soluble. The product may be washed, if desired, such as with hexane, heptane, and the like to remove unused starting materials. It is often not necessary to isolate the product, from the solvent, particularly if the solvent used is alcohol or water, since the product may be satisfactorily used for the present purposes in an aqueous or alcoholic solution.

There has been set forth, heretofore, the representations of E, X, R₁, and R₂. The reactants R₂X and

may be determined by combining the representations of the component parts previously listed. Typical of the reactants that may be employed as R₂X include octenyl chloride, nonenyl chloride, decenyl chloride, dodecenyl chloride, tetradecenyl chloride, hexadecenyl chloride, octadecenyl chloride, eicosenyl chloride, octadienyl chloride, decadienyl chloride, dodecadienyl chloride, octadecadienyl chloride, octatrienyl chloride, octynyl chloride, dodecynyl chloride, and octadecynyl chloride. The other anion representations of X, previously set forth, may be used in place of the illustrative chloride form presented above. The halide representation of X is preferred. Where more than one molecular location of X is possible in the reactant R₂X, all possibilities are contemplated as long as X is reactive in the present sense, that is, labile enough to undergo the present quaternization under the instant reaction conditions.

Typical of the reactants, having the formula

that may be used include N,N'-tetramethylethylenediamine, N,N'-tetraethylmethylenediamine, N,N'-tetramethylpropylenediamine, N,N'-tetraethylisopropylenediamine, N,N'-tetramethylbutylenediamine, 1,4-bis(diethylamino)-2-butene, 1,4-bis(dimethylamino)-1,3-butadiene, 1,4-bis(dimethylamino)-2-butyne, 1,2-dipiperidinoethane, 1,2-dimorpholinoethane, 1,2-dithiamorpholino-1-methyl-ethane, 1,4-dipyrrolidinylbutane, 1,4-dipiperidino-2-butene, 1,4-dimorpholino-2-butyne, N,N'-tetramethyl-2-hydroxypropylenediamine, N,N'-tetraethyl-2-hydroxypropylenediamine.

It is possible, and frequently advantageous, in the preparation of some of the present compounds to first prepare the halide form, such as chloride, in a manner already set forth, and then prepare any other desired form, within the present definition, by metathesis or ion-exchange methods. For instance, any of the present compounds in halide form, may be converted to the hydroxide form through the use of silver oxide, or the like, and then converted to any desired anion form by acidifying with an acid of choice such as sulfuric, phosphoric, acetic, and others within the range and spirit of this invention. In

The symmetrical diquaternary ammonium compounds of this invention are valuable non-durable anti-static agents for hydrophobic fibers, such as nylon, Dacron, and Orlon. They are useful fungicides, in a wide range of concentrations, for example, against *Stemphylium sarcinaeforme* and *Monilinia fructicola*. They are, also, effective bacteriostats and bactericides in dilutions of up to 1:50,000 and greater, particularly against *Micrococcus pyogenes* var. *aureus* and *Salmonella typhosa*. The present compounds exhibit advantageous characteristics as wetting, emulsifying, and dispersing agents and as detergents.

The compounds of this invention are valuable as detergent-sanitizers and may be employed in meat plants to sanitize cutting tables, grinders, and the like, in fruit processing operations, for instance, to wash and sanitize lemons, oranges, and grapefruit, and in dairy farms to sanitize dairy equipment and utensils.

A suitable detergent-sanitizer formulation for use in meat plants includes, by weight, 5% of a compound of this invention, 2.5 to 5.0% of octylphenoxyethoxyethanol, 20 to 40% soda ash, 20 to 40% sodium metasilicate, and the remainder sodium tripolyphosphate. One ounce of this formulation is used per gallon of water. For sanitizing citrus fruit there is preferably used one part of a present compound in 5000 parts of water. For use in dairy farms, there may be used 10% of a quaternary ammonium compound of this invention, 10% of octylphenoxyethoxyethanol, 7% of trisodium phosphate, and 73% of water. One ounce of this solution is used per four gallons of water. The instant compounds in aqueous solution, in amounts of about 0.5 to one ounce to one hundred pounds of dry fabric, are excellent as a final diaper rinse to prevent diaper rash. These compounds are, also excellent premise sanitizers where they may be employed in concentrations of about 0.1 to 2.0% in aqueous cleaning solutions.

The symmetrical diquaternary ammonium compounds of this invention and their method of preparation may be more clearly understood from the following examples, which are presented by way of illustration and not by way of limitation. Parts by weight are used throughout.

Example 1

There are added to a flask equipped with a thermometer, a reflux condenser and a stirrer 98.5 parts of N,N'-tetramethylethylenediamine, 400 parts of dodecenyl chloride, one part of sodium iodide and 1000 parts of isopropanol. The mixture is heated at reflux for 20 hours. The mixture is then concentrated to about one third of its original volume by means of distillation. The resultant solution is chilled and the crystals that form are filtered, washed twice with acetone and then dried in a vacuum desiccator. The white, hygroscopic, crystalline product contained 5.3% nitrogen (5.3% theoretical) and 13.6% chlorine (13.7% theoretical). The product corresponds to ethylenebis(dodecenyldimethylammonium chloride) and may be represented by the formula

similar manner, an anion-exchange resin may be employed. Any of the present compounds, in halide or hydroxide form, may be converted to any desired anion form through the use of an anion-exchange resin in the desired anion form. For instance, there may be used an insoluble, cross-linked, styrene-divinylbenzene copolymeric quaternary ammonium salt in its sulfate, phosphate, or like form to convert a present compound, in halide or hydroxide form, to a desired form, such as phosphate, sulfate, and the like.

In like manner, there is made from N,N'-tetraethylbutylenediamine and dodecenyl chloride the compound corresponding to the formula

Example 2

There are added to a reaction flask 77.5 parts of an aqueous 75% N,N'-tetramethylethylenediamine solution,

251 parts of dodecetyl chloride (84.5% pure) and 225 parts of water. The mixture is agitated and maintained at 60°-75° C. for 6 hours. The solution changes from

a yellow cloudy slurry to a clear amber solution as the reaction progresses. After this heating period, the equipment is modified to remove distillate, and 200 parts of water are added to the mixture. Approximately 200 parts of water plus some organic liquid are removed by this atmospheric distillation. The remaining liquid, a clear dark amber solution, corresponds to an aqueous solution of the product which contains 2.7% nitrogen (2.7% theoretical) and 7.5% chlorine (6.8% theoretical) for a 50% solution. The yield is 100%. The product may be named ethylenebis(dodecyltrimethylammonium chloride). To 56 parts of the above aqueous solution of product, there are added 224 parts of water and 0.06 equivalent of freshly prepared moist silver oxide. The mixture is stirred well at room temperature for one hour

and from N,N'-tetramethylbutylenediamine and 2,2,4,4-tetramethyl-16-chloro-6-hexadecene, there is obtained the compound having the formula

Example 4

A mixture of 14.4 parts of N,N'-tetramethylbutylenediamine, 49.7 parts of dodecetyl chloride and 300 parts of dry acetone is stirred at room temperature for 45 minutes. The solution is still clear indicating no substantial reaction has taken place at this temperature and time. The solution is then heated to reflux and 20 white precipitate starts to appear after 35 minutes. The reflux is continued for 24 hours. After cooling, the crystals that are formed are removed by filtration, washed once with dry acetone and dried in vacuum. The product melts at 194°-196° C. and contains 13.1% chlorine (12.9% theoretical) and 5.0% nitrogen (5.1% theoretical). The product corresponds to this formula

and then filtered. The residue is washed twice with 40 parts of water, and the washings are combined with the mother liquor. The combined aqueous solution contains less than 0.1% chlorine and indicates that about 95% of the original chloride ions have been replaced by hydroxide ions.

Example 3

A mixture of 13 parts of N,N'-tetramethylbutylenediamine, 47.5 parts of dodecetyl chloride, 0.3 part of sodium iodide, 50 parts of isopropanol and 50 parts of

35 In a similar way, a mixture of 14 parts 1,4-bis(dimethylamino)-2-butyne, 49.7 parts of dodecetyl chloride and 350 parts of acetone give some precipitate at room temperature in 25 minutes. After one hour of reflux, 300 parts of acetone is added to keep the mixture fluid. The mixture is refluxed for a total of 14 hours. After filtration, washing, and drying, the product is obtained. 40 It melts at 207°-209° C. and contains 13.2% chlorine (13.1% theoretical) and 5.0% nitrogen (5.2% theoretical). The product corresponds to this formula

acetone is refluxed for 16 hours during which time 43 parts of solvent is removed by distillation. The mixture is cooled. The crystals that separated out are

5 In a similar way, from ethylenedi-N,N'-piperidine and 1-bromo-2,4,6-octatriene, there is made the compound of this invention corresponding to the formula

washed twice with hot acetone and twice with cold acetone and dried under vacuum over calcium chloride. The white crystalline product melts at 101.5°-103° C. (with decomposition) and contains 13.6% chlorine (13.2% theoretical) and 5.1% nitrogen (5.2% theoretical). The product corresponds to trimethylenebis(dimethyl)dodecylammonium chloride).

In a similar way, from N,N'-tetraethylbutylenediamine and hexadecenyl bromide, there is made the compound of this invention corresponding to the formula

65 A mixture of 17.2 parts of N,N'-tetraethylbutylenediamine, 44.6 parts of 1-chloro-5-methyl-2-undecene, 0.5 part of sodium iodide and 125 parts of dry acetone is refluxed for 16 hours. The solution is concentrated by distillation and 300 parts of water added. The mixture 70 is then steam distilled until the oily layer is reduced to a small fraction. The oil is then removed in a separatory funnel. The aqueous solution containing the product weighs 352 parts and contains 2.0% chlorine (2.1% theoretical) and 0.84% nitrogen (0.80% theoretical).

fate, phosphate, acetate, citrate, and tartrate, which comprises bringing together the compounds

at a reacting temperature in the range of about 23° C. to the reflux temperature and thereby causing them to react in molecular proportions of substantially one of the former to two of the latter.

9. A method for the preparation of a symmetrical compound having the formula

in which the R₁ groups taken singly represent alkyl groups of not over two carbon atoms and taken collectively represent a divalent saturated aliphatic chain of four to five atoms which forms with the proximate nitrogen atom a five- to six-membered heterocyclic mono-amine group from the class consisting of morpholino, thiamorpholino, pyrrolidinyl, piperidino groups and these groups having a lower alkyl substituent, R₂ is an aliphatic hydrocarbon group of eight to twenty carbon atoms having at least one bond of unsaturation, E is a member of the class consisting of alkylene, alkenylene, alkynylene groups of two to four carbon atoms and a 2-hydroxy-propylene group and X is an anion from the class consisting of chloride, bromide, iodide, sulfate, methylsulfate, phosphate, acetate, citrate, and tartrate, which comprises bringing together in the presence of an inert volatile solvent the compounds

at a reacting temperature in the range of about 25° C. to the reflux temperature and thereby causing them to react in molecular proportions of substantially one of the former to two of the latter.

10. A method for the preparation of a symmetrical compound having the formula

in which the R₁ groups taken singly represent alkyl groups of not over two carbon atoms and taken collectively represent a divalent saturated aliphatic chain of four to five atoms which forms with the proximate nitrogen atom a five- to six-membered heterocyclic mono-amine group from the class consisting of morpholino, thiamorpholino, pyrrolidinyl, piperidino groups and these groups having a lower alkyl substituent, R₂ is an aliphatic hydrocarbon group of eight to twenty carbon atoms having at least one bond of unsaturation, E is a member of the class consisting of alkylene, alkenylene, alkynylene groups of two to four carbon atoms and a 2-hydroxy-propylene group and X is an anion from the class consisting of chloride, bromide, iodide, sulfate, methylsulfate, phosphate, acetate, citrate, and tartrate, which comprises bringing together in the presence of an inert volatile solvent and a polar iodide soluble in the reaction mixture the compounds

at a reacting temperature in the range of about 25° C. to the reflux temperature and thereby causing them to react in molecular proportions of substantially one of the former to two of the latter.

11. A method for the preparation of the symmetrical compound having the formula

in which R₁ is an alkyl group of no more than two carbon atoms, R₂ is an alkenyl group of eight to twenty carbon atoms, E is an alkylene group of two to four carbon atoms, and X is a halogen having an atomic weight of about 35.5 to 127, which comprises bringing together in the presence of an inert volatile solvent at a reacting temperature in the range of about 50° to 125° C. to the reflux temperature and thereby causing to react in molecular proportions of substantially one of the former to two of the latter the compounds

and R₂X.

12. A method for the preparation of

which comprises bringing together in the presence of an inert volatile solvent at a reacting temperature in the range of about 25° C. to the reflux temperature and thereby causing to react in molecular proportions of substantially one of the former to two of the latter N,N'-tetramethylethylenediamine and dodecyl chloride.

13. A method for the preparation of

which comprises bringing together in the presence of an inert volatile solvent at a reacting temperature in the range of about 25° C. to the reflux temperature and thereby causing to react in molecular proportions of substantially one of the former to two of the latter N,N'-tetramethylbutylenediamine and dodecyl chloride.

14. A method for the preparation of

which comprises bringing together in the presence of an inert volatile solvent at a reacting temperature in the range of about 25° C. to the reflux temperature and thereby causing to react in molecular proportions of substantially one of the former to two of the latter 1,4-bis(dimethylamino)-2-butyne and dodecyl chloride.

15. A method for the preparation of

which comprises bringing together in the presence of an inert volatile solvent at a reacting temperature in the range of about 25° C. to the reflux temperature and thereby causing to react in molecular proportions of substantially one of the former to two of the latter N,N'-tetramethyl-2-hydroxypropylenediamine and dodecyl chloride.

UNITED STATES PATENT OFFICE
CERTIFICATE OF CORRECTION

Patent No. 2,933,529

April 19, 1960

Jesse C. H. Hwa

It is hereby certified that error appears in the printed specification of the above numbered patent requiring correction and that the said Letters Patent should read as corrected below.

Column 7, line 53, column 8, line 71, and column 9, lines 26 and 59, after "unsaturation," each occurrence, insert -- from the class consisting of alkenyl, alkadienyl, alkatrienyl, and alkynyl groups, --; same column 9, lines 3 to 7, the formula should appear as shown below instead of as in the patent:

Signed and sealed this 20th day of September 1960.
